UNITED STATES PATENT OFFICE.

JOSEPH BARDSLEY, OF BROOKLYN, NEW YORK.

DOOR SPRING AND CHECK.

SPECIFICATION forming part of Letters Patent No. 366,711, dated July 19, 1887.
Application filed January 13, 1887. Serial No. 224,182. (No model.)

To all whom it may concern:

Be it known that I, JOSEPH BARDSLEY, a citizen of the United States, and a resident of Brooklyn, in the county of Kings and State 5 of New York, have invented certain new and useful Improvements in Devices for Hanging and Closing Doors, of which the following is a specification.

The invention relates to improvements in devices for hanging and closing doors; and it consists in certain elements of construction, hereinafter described, and particularly pointed out in the claims.

The apparatus sought to be protected here- 15 by is a further development and embodiment of the invention, with supplemental features, described and claimed in Letters Patent of the United States No. 329,000, issued to me on the 27th day of October, 1885.

20 The invention is illustrated in the accompanying drawings, forming a part of this application, in which Figure 1 is a top view of the apparatus as set into the floor beneath and in line with the width of the door. Fig. 2 is a 25 central vertical longitudinal section of same on the dotted line *a b* of Fig. 1, with the addition of a portion of the door. Fig. 3 is a horizontal longitudinal section of the same on the dotted line *c d* of Fig. 2, and Fig. 4 is a vertical transverse section on the dotted line *e f* of Fig. 1.

In the drawings, *A* designates the door, of usual construction, having embedded in its lower edge the bar *B*, which is secured in place 35 by screws, and is provided in its outer end with the vertical square aperture *C* to receive the upper end of the pivot *D*, forming a part of my invention. The pivot *D* is seated in one end of the casing *E*, so as to be capable of 40 rotation therewith, and is provided adjacent to that portion thereof which is immediately below the upper inner surface of the casing with the annular groove *F*, in which is placed the washer *G*, of elastic material, said washer 45 being preferably circular in cross-section. The pivot *D* is circular in outline from said washer to a point at the base of its squared upper end, which is adapted to enter the aperture *C* in the bar *B* above mentioned, and 50 upon one side of the pivot *D* is provided the substantially heart-shaped cam *H*, which,

when in its normal position, is in line with the length of the casing *E*, its broadest part being in a transverse line through and forming shoulders, one on each side of the pivot *D*, as 55 illustrated in Fig. 3 of the drawings. Upon opposite sides of the point of the cam are provided the corresponding depressions, *I J*.

The casing *E* forms a part of my invention, and consists of a flat upper part and substantially semicircular lower portion containing a circular bore, *K*, in which is placed the spring and piston, hereinafter described. The casing is intended to be embedded in the floor beneath the door, and is rigidly secured in position by means of screws entering the apertures *L*, formed in the laterally-extending portions of the upper part of the casing. The upper surface of the casing *E* is provided with a vertical opening, *M*, and the casing has an opening at each end, the former, when the invention is in use, being closed by the disk *N* fitting over the pivot *D*, and being held firmly in its seat against the metal washer *G'* by screws, as shown in Fig. 1, the rubber washer *G* being 75 thereby compressed and made to serve effectively as a packing, while the said end openings of the casing are threaded and adapted to be sealed by the screw-plugs *O P*, respectively.

It is essential that the casing be made liquid-tight, since a part of my invention involves the filling of the interior of the casing with a liquid, which will preferably be glycerine, and it is evident that the liquid will be 85 unable to escape, by evaporation or otherwise, while the apparatus is in use, owing to the plugs *O P* and the close-fitting disk *N* and washer *G*. It is also evident that the means which I have provided for sealing the interior 90 of the casing may be removed, when desired, to permit an inspection or the withdrawal of the interior operative mechanism. At a suitable point in the bore of the casing *E* are formed the inwardly-projecting lugs or stops *Q*, and that portion of the casing beyond the bore *K* and surrounding the pivot *D* is enlarged laterally on opposite sides, in order to provide sufficient space for the cam *H* during the rotation of said pivot, as shown in Figs. 1, 3, and 4. 100

The construction of the casing *E* above described is especially appropriate and desira-

ble for the purposes of the invention, since it may readily permit the insertion or withdrawal of the operative mechanism and liquid, may quickly be secured in position beneath 5 the door, and is liquid-tight, this latter consideration being of particular moment, since thereby the parts of the apparatus may be arranged in operative position and the liquid introduced therein by the manufacturer, and 10 thus shipped, ready to be connected with the door, whereby much time and annoyance must necessarily be saved to the purchaser in his not having to arrange the parts and apply the liquid, besides avoiding all danger of trouble 15 which might otherwise arise from his not having a practical knowledge of the mechanism. The casing E is also of advantageous construction, owing to the fact that it will occupy the minimum amount of space beneath the door 20 and will not be liable to collect dust or disfigure the apartment in which it is used.

Within the casing E is arranged the piston rod T, upon one end of which is secured the piston-head S, snugly fitting the bore K and containing 25 the apertures V, which are adapted to be opened and closed by the sliding valve-plate W during the movement of the piston-rod, as hereinabove described. Upon the opposite end of the piston-rod is secured or formed the yoke 30 X, inclosing the heart-shaped cam H, and consisting of the cross head or bar Y and the upper and lower pairs of arms, g h, extending rearward therefrom along the upper and lower surfaces of the cam H, as shown in Figs. 2, 3, 35 and 4, the rear ends of the upper fingers, g, being connected with the lower fingers, h, by pins i, which serve as axles for the vertical rollers j k, arranged immediately behind the side projecting portions of the cam H, as indicated more clearly in Fig. 3. The cross-bar 40 Y of the yoke X is provided on its side facing the cam H with the central pointed elevation, D', and on either side thereof the concave surfaces E' F', against which the said cam moves 45 during the rotation of the pivot D.

Upon the piston-rod T, adjacent to the cross-head Y, is the loose sleeve m, one end of which forms a collar, n, which is in contact with the stops Q, above mentioned, and serves as a bearing 50 for one end of the coiled spring R, which incloses the piston-rod and is held in a compressed condition between said collar and the piston-head S. The sleeve m has a broad surface in contact with and serves as a guide for 55 the piston-rod, and hence the collar n will not lose its relation to the stops Q or become otherwise disarranged or impaired by any sudden action of the operative parts of the apparatus, each element of which is specially constructed 60 with a view of durability in the most comprehensive sense of the word.

Within the casing E is formed a passage, t, one end of which opens into the bore K at its extreme outer end between the plug P and the 65 piston-head, while the other end of the passage opens into the vertical aperture w at a

point between the piston-head and collar n, as shown in Fig. 2, which aperture w is at its lower end in communication with the interior of the bore K, as shown, while its upper end is closed by means of the screw-plug x, the purpose of which, in addition to sealing the upper end of the aperture w, is to close to a greater or less extent, when and as desired, the passage t, thereby regulating the flow of 70 liquid through the same, as hereinabove described. The head of the screw-plug x, being exposed at all times above the casing E, may be readily turned by means of a screw-driver without disturbing the apparatus or disconnecting it from the door, and without any liability of the liquid escaping.

In addition to the passage t for conducting the liquid within the casing E around the piston-head S, there is provided also the passage 85 y, which is simply grooved into the surface of the metal of which the casing is constructed, as illustrated in Fig. 3, and whose outer end is closed by the piston-head when the latter is in its normal position, as shown.

If desired, the casing E when in use may be covered with a plate, z, (see Figs. 2 and 4,) of suitable material and finish, the same being secured to the casing by screws passing into the holes A' provided for them.

In instances where the surface into which the casing E is embedded is wood, the screws hereinbefore referred to, passing through the apertures I, will sufficiently secure the same; but when the apparatus is to be set into a 100 marble floor, for instance, additional securing means may be appropriately provided, and in such cases I make use of the wedge-shaped blocks B' B', held by screws beneath opposite sides of the upper part of the casing, as shown 105 in Figs. 1 and 4, which blocks are wider at their lower than at their upper end and have their sides taper inward toward the casing, as denoted by dotted lines in Fig. 1, and the purpose of which is to enable the casing being 110 firmly held in place by lead melted and poured around the same and hardened, and at the same time not interfere with the removal of the casing when necessary.

When it is desired to remove the casing secured by lead, as above specified, it will only be necessary to free the screws attaching the blocks B' B' to the casing and lift the latter from its bed, leaving the blocks therein. As far as this feature of the invention is concerned, 115 it must be understood that I do not confine myself to blocks B' B' which are wedge-shaped, strictly speaking, but claim for this purpose any blocks having projections or depressions which may be rigidly held by the lead and at 120 the same time be freed from the casing when desired. On opposite sides of the casing the laterally-projecting side portions of same are 125 removed, forming spaces m', through which the lead may be poured in order to embed the blocks B' B'.

In arranging the parts of the apparatus the

5 pivot D is inserted into its seat through the opening M, and the piston-rod carrying the yoke, collar n, spring, and piston-head (these elements having been previously put together) 5 then introduced through the right-hand end opening of the bore K, after which the rollers j k are inserted through the left-hand opening of the casing E into position between the arms g h, being there secured by the pins i, introduced through the opening M. The plug P, with its washers G G' and cap N, is then firmly secured in place and the liquid filled into the casing through the left-hand end of opening of same, the casing being turned upon its right-hand end for this purpose, after which the plug O is applied, as shown in Figs. 1 and 2, the apparatus being then in condition to be embedded into the floor, ready for connection with the door with which it may be 15 intended for use. The expansive force of the spring R is under the control of the manufacturer, and should be regulated according to the size of the door and other circumstances.

It will appear evident upon reference to 25 Figs. 2 and 3 that the compressed coiled spring R exerts a constant pressure against the piston-head in a direction away from the pivot D, and that said force controls in part the relation of the yoke X with the heart-shaped 30 cam H, the side projecting portions of which in contact with the rollers j k operate as checks to prevent the yoke being moved from the cam and as surfaces acting upon said rollers to force said yoke toward the pivot D against the compression of the spring R during the opening of 35 the door.

In the operation of the apparatus the door, being pushed open in either direction, will cause the pivot D to turn in its seat, and thus 40 bring the cam H against one of the rollers j k, forcing the same, and through it the piston-rod and piston, inward, or toward the pivot D, the liquid within the casing during this movement passing through the apertures V in the piston-head and through the passages t and y leading around said head, this being necessary in 45 view of the fact that the casing is about filled with the liquid and part of it must pass to the opposite side of the piston-head in order 50 to permit the movement of the latter.

The operation of the valve-plate W will be 55 readily understood, the force of the liquid merely causing it to slide forward on the stem supporting it, thereby opening the apertures V. The movement above described of the piston-rod and piston-head, due to the opening of the door, operates to compress the coiled 60 spring R between said head and collar m, the latter remaining stationary, thereby creating an increased force therein which will operate to move the piston to its former position, and thus rotate the pivot D back to its normal condition and close the door as soon as the latter is free from the power which opened it. During 65 the latter movement of the piston and piston-head to their initial condition the liquid

in front of said head will return to the opposite side of the head through the passages t and y aforesaid, the valve-plate W during this movement closing against the apertures V. Owing to the relative positions of the passages t and y, the piston-head will close the latter before it has fully attained its normal position, the passage t remaining open, the purpose of this arrangement being to allow the liquid to flow more freely during the time the door is making the first part of its movement and checking said flow during the latter part of said movement, in order that the door may not close violently. If at any time it should be desired to have the liquid flow more freely or less freely through the passage t, this result may be accomplished by merely adjusting the screw-plug x to cover more or less of the said passage. The form 85 of cam H and its position in the yoke X is such that the door may be opened with equal facility in either direction, and in either event the spring, piston-rod, and piston operate in the same manner. The sleeve m, being in contact with the rigid stops Q, is prevented from losing its position and renders it impossible for the spring to be acted upon in any other manner than its direct compression and expansion. During the rotation of the pivot D in 90 either direction the point of the heart-shaped cam H moves over one of the concave surfaces E' E' of the cross-bar Y, one of the side projecting portions of said cam being brought against one or the other of the rollers j k 95 without undue friction, and creating thereby a positive movement of the piston and piston-rod toward the pivot D. The construction of the yoke X and cam H are matters of great importance, since thereby I am enabled to produce an apparatus which will not be liable to become deranged or broken, and which will operate positively and smoothly without noise or jarring. During the rotation of the pivot D the point and side projecting parts of the cam H closely follow their contact-surfaces smoothly, positively, and without obstruction, and prevent any sudden or irregular action in the spring R. The passages t and y for the liquid are also of great 105 importance, since thereby the force with which the door is closed may be regulated at will, according to its size and the circumstances attending its use, and said door when closing 110 may be caused to stop at its closing-point without passing the center, if it be a double-acting door, and without "banging" if it be a single-acting door.

In instances where it may not be of moment to regulate the force with which the door shall close it will not be essential to employ a liquid within the casing E, and the passages t y and apertures V may be dispensed with. In such instances, also, the casing need not be made liquid-tight.

What I claim as new, and desire to secure by Letters Patent, is -

1. In apparatus for hanging and closing doors, the piston, piston-rod, spring, and yoke, the latter consisting of the cross bar and arms extending rearward therefrom, combined with the actuating-pivot in communication with the door and carrying the heart-shaped cam H, inclosed within and adapted at its front and rear ends to engage the adjacent portions of the said yoke during the operation of the apparatus, the said cross-bar affording a contact-surface for the front end or point of the cam, substantially as and for the purposes set forth.
2. In apparatus for hanging and closing doors, the liquid-tight inclosing-casing, combined with the actuating-pivot seated in the casing and being in communication with the door, the piston, piston-rod, spring, stop for the spring, the passage t, formed in the casing and extending from one side of the piston-head to the other, the vertical aperture w, also formed in the casing and being in communication with the passage t, and the adjusting-plug x, arranged in the aperture w and adapted to be adjusted from the outside of the casing, substantially as and for the purposes set forth.
3. In apparatus for hanging and closing doors, the liquid-tight inclosing-casing E, composed of the lower part or body having the bore K and the upper flat part, and provided with the cap N and threaded plugs O P to close correspondingly-shaped openings therein, combined with the piston, piston-rod, spring, stop, yoke, actuating-pivot in communication with the door, and the cam car-
- ried by the said pivot within and being adapted at each end to engage the said yoke during the operation of the apparatus, substantially as and for the purposes set forth.
4. In apparatus for hanging and closing doors, the actuating-pivot, piston-rod, piston-head, spring, and stop, combined with the inclosing-casing containing a liquid and provided with the passages lettered t y, respectively, of such respective length that one may be closed by the piston-head before reaching its normal position, while the other remains open, substantially as set forth.
5. In apparatus for hanging and closing doors, the casing inclosing the operative mechanism and having a flat upper surface with projecting flanges, combined with anchor-blocks B' B', substantially as and for the purposes described.
6. In apparatus for hanging and closing doors, the casing inclosing the operative mechanism and having a flat upper surface with projecting flanges suitably apertured for the reception of screws and provided with openings for the introduction of molten lead, combined with the covering-plate secured to and concealing said casing, substantially as and for the purposes set forth.

Signed at New York, in the county of New York and State of New York, this 11th day of January, A. D. 1887.

JOSEPH BARDSLEY.
